UNITED STATES PATENT OFFICE.

WALTER P. HOOKER, OF SALISBURY, NORTH CAROLINA.

SEWERAGE DISPOSAL TANK.

1,406,385.

Specification of Letters Patent. Patented Feb. 14, 1922.

Application filed April 2, 1921. Serial No. 458,146.

To all whom it may concern:

Be it known that I, WALTER P. HOOKER, a citizen of the United States, and a resident of Salisbury, in the county of Rowan and State of North Carolina, have invented a new and useful Improvement in Sewerage Disposal Tanks, of which the following is a specification.

My invention relates to sewerage disposal tanks for use in communities not equipped with the modern sewerage disposal systems.

In tanks of this character or what are usually known as septic tanks a plurality of communicating tanks or separate chambers are employed wherein the human excrement passes through the several tanks or compartments and in each is subjected to bacterial action and is finally permitted to drain in the ground in a purified liquid state.

The main object to tanks of this character is that one or more tank compartments settles or sinks deeper in its foundation which obviously throws the pipes connecting the tanks together out of alinement which cracks the pipes or causes leaky joints. It will be thus seen that liquid passing through the cracked pipes or broken joints will pass into the ground and thereby contaminating the same and rendering unsanitary conditions.

With these objections in mind it is the primary purpose of my invention to provide a sewerage disposal tank including a plurality of compartments or chambers all of which are positively locked together and thereby making it impossible for relative movement of the individual chambers or compartments.

It is a further object of the invention to provide a sewerage disposal tank embodying a plurality of chambers or compartments which will be placed in coinciding relation in the ground and cemented or united in a novel manner.

With the preceding and other objects and advantages in mind, the invention consists in the novel combination of elements, construction and arrangement of parts and operations to be hereinafter more fully described, claimed and illustrated in the accompanying drawings wherein,

Figure 1 is a side elevation of my improved tank in operative position, parts being broken away;

Fig. 2 is a top plan view of the same, having parts broken away;

Fig. 3 is a perspective of one of the tank sections;

Fig. 4 is a vertical sectional view of the latter, and

Fig. 5 is a fragmentary detail perspective.

Referring in detail to the drawings wherein corresponding characters of reference designate corresponding parts throughout the several views the numeral 5 designates a tank moulded from reinforced concrete or other plastic composition and includes a removable cover 6. As is illustrated in the drawings, the tank 5 is substantially cylindrical and is formed at one side with a flat or straight wall 7 so that two tanks may be arranged in mating relation as shown in Fig. 2. The outer face of each wall 7 is provided with dove-tail channels or grooves 8 and the grooves or channels of one flattened wall registered coincident with the grooves of the other wall, thereby providing longitudinal key-ways 9 in which cement or the like is poured to provide a bond or key 10 between two compartments or tanks. The flat walls 7 are of greater thickness than the other walls of the compartments and when united as above set forth reinforce each other.

Formed with the inner face of each tank or compartment 5 and located at diametrically opposite points are semi-circular walls 11 which extend from the upper end of the tanks or sections to a point below the surface of the liquid contained in these tanks. As is shown in Fig. 2, the tanks are arranged so that one pair of walls 11 are adjacent each other and communicating with these compartments or chambers at these points is a short pipe connection 12. An inlet pipe 13 leads to one of the compartments or chambers 5 at a point where the other wall 11 is disposed and extending from the other compartment or chamber 5 at a point where its wall 11 is disposed is an outlet pipe 14 which extends to a suitable drain bed. These walls 11 in addition to directing the passage of the sewage through the compartments serve to brace or reinforce the sections.

In use it will be obvious that the sewage passing through the pipe 13 will pass into the first chamber or compartment 5 where it is subjected to bacterial action and thence through the pipe 12 and discharged into the other compartment or chamber 5 where it is

subjected to further bacterial action and the decomposition of all foreign matter. From this point the sewage is let off to the drain bed through the pipe 14 in a purified liquid state.

It is to be understood that the form of my invention herein shown and described is to be taken as a preferred example of the same, and that various changes in the shape, size 10 and arrangement of parts may be resorted to without departing from the spirit of the invention or the scope of the subjoined claims.

Having thus described my invention, what 15 I claim as new and desire to secure and protect by Letters Patent of the United States is:

1. An apparatus of the character described comprising a plurality of chambers, 20 each having a flattened face and adapted to be buried in the ground with the flattened

faces abutting each other, the flattened faces being provided with vertically disposed registering grooves, and a plastic bond filling the grooves whereby to prevent one chamber from sinking with respect to the other the flattened ends serving to reinforce each other.

2. In a sewerage tank, a plurality of chambers each provided with a flattened 30 face and adapted to be buried in the ground with the flattened faces abutting each other, the flattened faces being of relatively great thickness and provided with vertically disposed registering grooves, and a plastic bond 35 filling the grooves to lock the flattened faces together and thereby prevent the chambers from sinking with respect to each other, the flattened faces also serving to reinforce each other.

WALTER P. HOOKER.
